UNITED STATES PATENT OFFICE.

JOHN J. HILLIARD, OF FORT WORTH, TEXAS, ASSIGNOR TO BAKER ICE MACHINE COMPANY OF TEXAS, OF FORT WORTH, TEXAS, A CORPORATION OF TEXAS.

CONDENSER.

Application filed February 4, 1927. Serial No. 165,863.

My invention relates to condensers which are commonly employed as parts of ice-making machines of the ammonia compression type, and which individually comprise an external tube for the refrigerant and a plurality of connected internal tubes for water or a like cooling medium. It likewise relates to similar structures which operate reversely by evaporation in brine coolers and the like, and which are herein and in the subjoined claims classified as condensers. It is a main object of the invention to minimize leakage, and to prevent ammonia from escaping into the water used in condensers of the specified class; to render the inner tubes and the outer tubes of such condensers mutually adjustable in compensation for their unequal longitudinal expansion and contraction caused by the thermal changes to which they are operatively subjected; to eliminate from the interior of the outer tubes all joints and pipe bends between the inner tubes or parts thereof; to effect the mutual adjustment of inner and outer tubes automatically during their use; to expedite and facilitate the discovery and stoppage of all leakages in condensers of the specified class; to stop such leakages, if any, by operative adjustment of parts of the condensers, without dismantling the apparatus and without recourse to structural repair; to make the inside of the inner tubes readily accessible for cleansing and the like; and in general to attain collectively in condensers of this class all the advantages, without the disadvantages, which pertain to double-pipe condensers in general.

To accomplish these results I incorporate in my improved condenser, either singly or in numbers, as parts thereof, an outer tube, shell, or casing, which has terminal heads hereinafter called ammonia heads a plurality of inner tubes which extend, without joints or pipe bends, through the interior of a single outer tube and through its heads, a pair of outer heads spaced from the ends of the outer tube, and having water passages communicating with the inner tubes; an apertured intermediate head slidable on the water tubes between each water head and the adjacent ammonia head, a correspondingly apertured gasket between each outer head and the adjacent intermediate head, packings and a detector ring which encircle each inner tube between each ammonia head and the adjacent intermediate head, means for mutually adjusting the adjacent heads, and inlet and outlet water pipes which pass through stuffing-boxes in the opposite outer heads respectively.

In said drawings, which illustrate the best manner wherein I have contemplated applying the principles of the invention, Figure 1 is a partial elevation of the right hand end of a multiplex condenser comprising a plurality of connected single, or shell and tube, condensers which are constructed in accordance with these principles. The rest of the figures are details. Fig. 2 is an elevation of the inner side of the left hand waterhead. Fig. 3 is a section on section line 3—3 of Fig. 2. Fig. 4 is an enlarged portion of Figures 7 and 8, including one of the detector rings. Fig. 5 is a side elevation of one of the intermediate heads. Fig. 6 is a section on the section line 6—6 of Fig. 5. Figures 7 and 8 are axial sections of a left hand end portion of the condenser of Fig. 1 on the section lines 3—3 and 7—7 respectively of Fig. 2. Fig. 9 is a partial end elevation of the right hand end of the condenser of Fig. 1.

In these drawings the outer tubes—of which two are shown in Fig. 1—are duplicate cylindrical steel shells, which are denoted by the numerals 1. They have ammonia inlet pipes 2 and 2' respectively, and ammonia outlet pipes 3 and 3' respectively. Each of them has at each end an ammonia head 4 and a perforated peripheral flange 5. These heads are formed integrally with the outer tube and have for the accommodation of the inner tubes the holes 6, which are counterbored from the outside for the packings which are hereinafter described. The inner tubes, of which the odd number seven are shown in each ammonia tube, are a group of duplicate spaced pipes denoted by the numerals 7. They are a little longer than the outer tubes in which they are placed, and project adjustably through the counterbored holes 6 in the ammonia heads. The outer heads 8 and 9 are a pair of flanged iron castings facing toward each other at the opposite ends respectively of each single condenser. The head 8 contains the chambers, channels or water passages 10, 11 and 12, opening in and through its face,

and registering and intercommunicating with individual pairs respectively of the inner tubes 7; and also contains the water passage 13, piercing the head in the direction of its thickness and in axial alinement with the single unpaired water tube 7, and having at the back of the head the discharge outlet 14. In the multiplex condenser shown in Fig. 1 this outlet has a waste pipe 15 leading through the stuffing-box 16 to the waste-pipe header 17. In like manner the outer head 9 contains the water channels 10', 11' and 12', similar to the channels 10, 11 and 12, and a perforating water passage 15 which is similar to the passage 13, and is axially alined with the end of the supply pipe 15'. The latter leads from the supply-pipe header 17' through a stuffing-box to this alined water tube. Thus the heads 8 and 9, without the aid of any pipe bends, complete a continuous connection of the inner tubes in series between the supply pipe 15' and the outlet pipe 15.

The intermediate head 18 is a circular steel plate located between each outer head and the adjacent ammonia head. It has perforations 19 for the inner tubes 7 respectively; and these perforations are counterbored in the side of the intermediate head 30 which is next to the ammonia head, for the packings 24, which are hereinafter described. It has a plurality of screws, or studbolts, 20, projecting from its opposite sides. Between each intermediate head and the adjacent outer head is placed a gasket 21, which has openings corresponding respectively to those in the face of the outer head itself.

The detector rings 22 are cylindrical or sleeve-like, and have their opposite ends in parallel planes at right angles with their axes. They are formed of Babbitt metal or the like and are severally adjustable by sliding on the water tubes 7 respectively between the ammonia heads and the adjacent intermediate heads. Each ring has a plurality of vent holes 23 extending from its hollow interior to its peripheral exterior. Contiguous to the opposite ends respectively of each detector ring, and similarly encircling the water tubes 7, are two pairs of resiliently compressible gaskets 24, formed of india rubber or the like and adapted to serve as packings in the counterbored perforations 6 and 19 of the adjacent heads 4 and 18.

For the purpose of manually adjusting, and of holding, the described heads in appropriate positions relative to each other, the flanges of the outer heads and of the outer tubes are perforated by the bolt-holes 25, which are occupied by the stud bolts 20, having nuts 26.

For the purposes of initial adjustment of the condenser, and for the stoppage of leaks, the intermediate heads are operatively ap-

proximated to the adjacent outer heads and to the adjacent ammonia heads by an attendant by turning the appropriate nuts 26; but all ordinary and slight mutual adjustments of the heads, normally requisite during the operation of the condenser, are effected automatically by the compression and expansion of the resilient gaskets 24 caused by unequal expansions and contractions of the inner and outer tubes. If any ammonia should chance to leak past the resilient gaskets in the ammonia heads, and if any water should leak past any of those in the intermediate heads, the same will be immediately discovered escaping through the open vent-holes 23 in the detector rings.

I claim as my invention—

1. In a condenser of the specified class, an outer tube having a terminal head, a plurality of inner tubes projecting through the terminal head, an outer head having passages therein for intercommunication with the inner tubes, and means including an intermediate head for adjusting the inner tubes to the outer head.

2. In a condenser of the specified class, an outer tube having a terminal head, a plurality of inner tubes projecting through the terminal head, an outer head having passages therein for intercommunication with the inner tubes, and means including a resilient member, for adjusting the inner tubes to the outer head.

3. A condenser of the specified class, comprising an outer tube having terminal heads, a plurality of inner tubes projecting through the terminal heads, a pair of outer heads having passages therein for connecting the inner tubes, a pair of intermediate heads having apertures for the inner tubes respectively, apertured gaskets between the outer and the intermediate heads, packings on the inner tubes between the terminal and intermediate heads, detector rings on the inner tubes between the packings, and screws for mutually connecting and adjusting the heads.

4. In a condenser of the specified class, an outer tube having a terminal head, a plurality of inner tubes projecting through the terminal head, an outer head having passages therein for intercommunication with pairs of the inner tubes respectively, an intermediate head having perforations for the inner tubes respectively, compressible packings on the inner tubes between the terminal and the intermediate heads, and detector rings between the packings on the inner tubes respectively, in combination with means including screws for mutually connecting and adjusting the heads.

5. A condenser of the specified class, comprising an outer tube having terminal heads, a plurality of inner tubes projecting through the terminal heads, a pair of outer heads

having passages therein for terminally connecting the inner tubes in series, a pair of intermediate heads having apertures for the inner tubes, resiliently compressible packings on the inner tubes between the terminal and intermediate heads, detector rings between the packings on the inner tubes, and means including screws for mutually adjusting the heads.

6. In a condenser of the specified class, a metallic plate of general circular form having a plurality of screw bolts projecting from its opposite sides, near the margin of the plate, for engagement with a water head at one side of the plate and with an ammonia head at the other side of the plate, and having a plurality of counterbored holes

through the plate for slidable water pipes and packing.

7. In a condenser of the specified class, an outer tube having a terminal head, a plurality of inner tubes projecting through the terminal head, an outer head having passages therein for intercommunication with pairs of the inner tubes respectively, an intermediate head having perforations for the inner tubes respectively, and resiliently compressible packings on the inner tubes between the terminal and intermediate heads, in combination with means including screws for mutually adjusting the heads.

Witness my signature at Fort Worth, Texas, January 22, 1927.

JOHN J. HILLIARD.
